PAINT BRUSH

William Wagner, Absecon, N.J.

Application August 2, 1957, Serial No. 676,021

4 Claims. (Cl. 15—248)

This invention relates to improvements in paint brushes and, more specifically, the invention pertains to the provision of a drip cup or receptacle for receiving paint from the paint brush when the same is held in an inverted position.

One of the primary objects of this invention is to provide in a paint brush means intermediate the brush bristles and handle for receiving paint from the bristles when the brush is inverted for overhead painting.

Another object of this invention is to provide in a paint brush a receptacle disposed intermediate the brush bristle and handle, the receptacle receiving drippings from the bristles when the brush is inverted, the receptacle having flexible side walls which are flexed for extruding the accumulated paint therein to return the paint to the bristles.

A further object of this invention is to provide a paint brush of the type referred to supra, the brush having means thereon for receiving paint runback from the bristles when painting overhead, the means being operable to return the runback paint to the bristles with a consequent attendant reduction in waste paint and the resulting reduction of material costs.

This invention contemplates, as a still further object thereof, the provision of a paint brush of the type generally described above, the paint brush being non-complex in construction and assembly, inexpensive to manufacture, and durable in use.

Other and further objects and advantages of the instant invention will become more evident from a consideration of the following specification when read in the light of the annexed drawing, in which:

Figure 1 is a side elevational view of a paint brush constructed in accordance with the teachings of the present invention;

Figure 2 is a detailed, vertical, cross-sectional view taken substantially on the line 2—2 of Figure 1, looking in the direction of the arrows;

Figure 3 is a detailed, cross-sectional view taken substantially on the vertical plane of line 3—3 of Figure 2, looking in the direction of the arrows;

Figure 4 is a detailed, transverse cross-sectional view taken substantially on the horizontal plane of line 4—4 of Figure 3, looking in the direction of the arrows;

Figure 5 is an exploded perspective view of one of the connecting devices utilized in the assembly of the paint brush;

Figure 6 is a detailed, cross-sectional view similar to Figure 2 but inverted with respect thereto to illustrate the return of the runback paint to the brush bristles;

Figure 7 is a perspective view of a paint brush constructed in accordance with this invention and illustrating the manner by which the paint accumulated in the receptacle is extruded for return to the bristles; and

Figure 8 is a fragmentary perspective view of a second embodiment of this invention.

Referring now more specifically to the drawing, reference numeral 10 designates, in general, a paint brush

2

constructed in accordance with the teachings of this invention. The paint brush 10 is seen to comprise an elongated handle 12 having an elongated substantially rectangular base 14 integrally connected with one end of the handle 12 and extending transversely with respect thereto. The base 14 is provided with a pair of laterally spaced inwardly extending threaded openings 16 which receive the threaded ends 18 of a pair of bolts 20. The other ends of the bolts 20 are provided with enlarged substantially rectangular heads 22 having threads 24 extending inwardly from the upper ends thereof. An elongated substantially rectangular plate 26 is superposed over the headed ends 22 of the bolts 20, the plate having a pair of spaced apertures 28 extending transversely therethrough adjacent each end thereof, respectively. The apertures 28 are coaxially aligned with the bolts 20.

To serve a purpose to be described below, the plate 26 is provided with a plurality of laterally and longitudinally extending struts 30.

Disposed in juxtaposition with respect to the plate 26 is a substantially rectangular bristle block 32 having one end of a plurality of paint brush bristles 34 fixedly secured therein in the conventional manner. The block 32 extends longitudinally of the plate 26 and is provided with an opening 36 at each of its respective ends through which extend screws 38 for threaded engagement with the internal threads 24 of the head 22 of the bolt 20.

Reference numeral 40 designates a substantially rectangular casing formed of rubber or of a flexible plastic material, the casing 40 having a pair of opposed open ends. A metallic channel-shaped stiffening element 42 receives one open end of the casing 40 therein and is fixedly secured thereon. The other open end of the casing 40 is secured to the base 14 as by nails or tacks 44.

As is seen in the figures, the struts 30 engage the inner side wall 46 of the channel-shaped stiffening element 42 to form passages 48 between adjacent portions of the element 42 and the plate 26.

The brush 10 is manually operated in the conventional manner, the casing 40 possessing sufficient rigidity to prevent the tearing of the bristles 34 relative to the handle 12. However, the paramount advantage of the brush of the present invention over conventional paint brushes becomes most evident when engaged in painting overhead. Under such conditions, the brush 10 is utilized in the positions illustrated in Figures 1 to 3, inclusive.

It will be seen that the casing 40, the base 14 of the handle 12 and the plate 26 supporting the block 32 all cooperate to define a substantially rectangular hollow paint receiving cavity 41. The passages 48 between the plate 26 and the element 42 are in open communication with the cavity 41 and provide means for ingress and egress of the paint.

In engaging in such overhead painting, the brush bristles 34 may be saturated to their maximum paint retaining capacity and, as is now obvious, any paint runback or drip towards the handle 12 due to gravity will pass from the bristles 34 through the passages 48 into the cavity 41.

At any time after paint begins to accumulate within the cavity 41 the operator may invert the brush 10 from the position shown in Figures 1 to 3, inclusive, to the positions shown in Figures 6 and 7, and through the simple expedient of squeezing the casing 40 in the manner illustrated in Figure 7 the paint accumulated therein will be extruded through the passages 48 back upon the bristles 34.

A second embodiment of this invention is illustrated in Figure 8. In this embodiment elements thereof finding counterparts in the first embodiment carry identical reference numerals to which has been added a prime mark for identification purposes.

As is illustrated in Figure 8, a sponge 60 is disposed within the casing 40' and occupies substantially all of the space within the cavity 41'. The sponge 60 is provided for absorbing paint accumulated within the casing 40' when the brush user changes from overhead painting to general painting, such as, for example, to wall painting. Under such circumstances, the paint accumulated within the casing 40' would have a tendency to leak back through the openings or passages 48 (see Figure 4) causing undesirable drip and paint wastage.

In all other respects, the two embodiments of this invention are identical.

While the above-mentioned element 60 has been recited as being formed of sponge material, it is to be understood that any other suitable and desirable liquid absorbing material may be substituted therefor.

Having described and illustrated two embodiments of this invention in detail, it is to be understood that the same are offered merely by way of example, and that this invention is to be limited only by the scope of the appended claims.

What is claimed is:

1. A paint brush comprising a handle having a base at one end extending transversely thereof, a bristle block support plate, means fixedly securing said plate to said base in spaced relation relative thereto, a bristle block having a plurality of bristles projecting from a side thereof, means fixedly securing said bristle block to said plate, a flexible casing extending between said base and said plate, said casing, said base of said handle and said bristle block cooperating to define a paint receiving cavity, means fixedly securing one end of said casing to said base, and means connecting the other end of said casing to said plate in spaced relation relative thereto, a channel-shaped element fixedly secured to said other end of said casing, and said last named means comprising a plurality of struts projecting laterally from said plate and connected with said element to form paint runback passages between said plate and said casing.

2. A paint brush comprising a handle having a base at one end extending transversely thereof, a bristle block support plate, means fixedly securing said plate to said base in spaced relation relative thereto, a bristle block having a plurality of bristles projecting from a side thereof, means fixedly securing said bristle block to said plate, a flexible casing extending between said base and said plate, said casing, said base of said handle and said bristle block cooperating to define a paint receiving cavity, means fixedly securing one end of said casing to said base, means connecting the other end of said casing to said plate in spaced relation relative thereto, a sponge material disposed in said flexible casing and occupying substantially the entire space between adjacent sides of

5 said base and said bristle block support plate, a channel-shaped element fixedly secured to the other end of said casing, and said means connecting the other end of said casing to said plate comprising a plurality of struts projecting laterally from said plate and connected with said element to form paint runback passages between said plate and said casing.

3. A paint brush comprising an elongated handle having an elongated substantially rectangular transverse base integral therewith, said base having a plurality of laterally spaced inwardly extending threaded openings, said openings receiving threaded ends of a like plurality of substantially cylindrical bolts, the other ends of said bolts having enlarged head portions internally threaded from the outer ends thereof, an elongated substantially rectangular plate superimposed over said enlarged head portions, said plate having a plurality of apertures formed therein in coaxial alignment with said internally threaded enlarged head portions, a substantially rectangular bristle block having a plurality of bristles fixedly secured to one side thereof, said block being in juxtaposed relation relative to said plate, a plurality of openings in said block coaxially aligned with said apertures formed in said plate, screws extending through said aperture and said openings and threadedly connected with said enlarged head portions, a substantially rectangular flexible casing having a pair of opposed open ends, a rigid channel-shaped stiffening element fixedly secured to one of said open ends of said casing, the other of said open ends of said casing being fixedly secured to said base of said handle, said casing, said base of said handle and said plate cooperating to define a paint receiving cavity, a plurality of laterally and longitudinally extending struts projecting from said plate, one end of said struts being fixedly secured to said plate and the opposed ends of said struts being fixedly secured to said channel-shaped element, said struts being in spaced relationship relative to one another so that passages are formed between each adjacent pair thereof, said passages being in open communication with said paint receiving cavity.

4. A paint brush as defined in claim 3, wherein said paint receiving cavity is substantially filled with an absorbent material.
